GRID SUPPORT STRUCTURE

Lucien B. Curtis, Verona, N. J., assignor to Radio Corporation of America, a corporation of Delaware

Application April 30, 1946, Serial No. 665,954

9 Claims. (Cl. 250—27.5)

1

The present invention relates to electron discharge tubes for superheterodyne reception which, more specifically, utilizes converter type tubes having multiple grids.

The need for portable radio and electronic equipment and the demands of high frequency reception create the outstanding problem of reducing the size of the tube structure. In the solution of this problem, however, the decrease in the size of the electron discharge tubes is physically limited in one respect by the need for necessary spacing of the electrodes within the envelope to provide sufficient insulation between the several electrode structures. Also, there is a further limitation due to the increase of cost of manufacture relative to the decrease of the size of tube structure.

One solution of the problem has been to utilize the envelope of a metal tube as the plate electrode. However, this has introduced new problems of insulation and cooling.

An object of this invention is the arrangement of the tube structure in a novel manner so as to reduce the diameter size of the tube.

A more particular object of the invention is to provide a common support for two equipotential grids without destroying the utility of the space between the grids.

My tube construction helps to solve the problem of reducing the size of tube structure in providing a more compact arrangement of the electrode elements by eliminating one set of supporting side rod members within the envelope and utilizing another set of side rod members as a common support for two separate but equipotential grids. This arrangement is so devised as to provide an unobstructed space between the two grids for the mounting of a third grid.

The novel features which I believe to be characteristic of my invention are set forth with particularity in the appended claims, but the invention itself will best be understood by reference to the following description taken in connection with the accompanying drawing, in which—

Fig. 1 is a cross-section transverse to the longitudinal axis of a conventional tube of the converter type;

Fig. 2 is a view in perspective, with parts removed, of an electron discharge tube embodying my invention;

Fig. 3 is a cross-section of the tube of Fig. 2 along line 3—3 according to my invention; and

Fig. 4 shows a detailed form of a grid structure according to my invention.

In Fig. 1 is disclosed a conventional tube of

the converter type having a cathode K. A series of concentric grids G₁ through G₅ are disclosed surrounding the cathode K. A cylindrical plate P is also mounted concentric with the cathode and enclosing the series of grids. All these structures are enclosed within the envelope E of the tube. In this tube in Figure 1, grids G₂ and G₄ are screen grids of the same potential and are connected together within the tube as is well-known in the art.

Figs. 2 and 3 disclose in detail my invention. The tube, disclosed in these figures, has an envelope 2. Insulating spacers 3 at the top and bottom of the tube hold in alignment the cathode 4 and the electrode supporting side rods 7, 9 and 13. Spaced outwardly from the cathode and in concentric arrangement (Fig. 3) are the control grid 6, screen grids 8 and 12, signal grid 10, suppressor grid 14, and plate 16. Control grid 6 is supported by side rods 7. Screen grids 8 and 12 corresponding to grids G₂ and G₄ of Fig. 1, are mounted on common side rods 9. This arrangement is possible as these screen grids 8 and 12 operate at the same potential. In the preferred form of my invention the inner grid 8 is formed as an elliptical right section of a cylinder, while screen grid 12 is of a circular cylindrical shape. These two grids are brought close together at two points along the transverse axis of the elliptical grid 8, in such a manner as to be supported by the common supporting rods 9. This arrangement leaves enclosed and unobstructed spaces 5 between the outer surface of the screen grid 8 and the inner surface of the screen grid 12. These enclosed spaces are utilized in mounting a foraminous electrode such as a signal electrode 10 upon side rods 11. To conform with this arrangement, the signal electrode 10 is preferably made of two parts, one of which is shown in detail in Fig. 4, each part being supported by one rod 11. This preferred form of the grid may comprise a mesh reinforced at the top and bottom by metal straps 15. The two parts of grid 10 are of cylindrical form and one is mounted in each of the unobstructed spaces 5 between grids 8 and 12. Furthermore, the parts of grid 10 are preferably concentric with the cathode 4.

It is obvious that other types of control electrodes, well known in the art, may be substituted for the particular structure of Fig. 4. If it is desired to provide a larger space 5, the grid 12 can also be formed with an elliptical section which has its transverse axis perpendicular to the plane of the common support rods 9. Grids

8 and 12 may be either mesh or wound as is well known in the art.

Thus, the equipotential grids of a converter tube, are arranged in a much smaller space and in such a way as to provide between them an unobstructed space for the positioning of a third grid. Furthermore, this third grid, 10, of my invention, is designed so as to utilize this unobstructed space between the equipotential grids 8 and 12. Furthermore, by supporting the two equipotential grids upon common side rods, one pair of supporting side rods of the conventional type tube is eliminated.

While certain specific embodiments have been illustrated and described, it will be understood that various changes and modifications may be made therein without departing from the spirit and scope of the invention.

What I claim specifically is:

1. An electron discharge device comprising a first grid and a second grid, a support rod supporting both said first grid and said second grid, said second grid completely enclosing said first grid and forming with said first grid an unobstructed space therebetween, and a control electrode mounted within said space.

2. An electron discharge device comprising a first screen grid and a second screen grid, a plurality of support rods each supporting both said first screen grid and said second screen grid, said second screen grid completely enclosing said first screen grid and forming with said first screen grid an unobstructed space therebetween, and a control electrode mounted within said space.

3. An electron discharge device comprising a plurality of support rods, a first screen grid mounted on said support rods, a second screen grid also mounted on said support rods, said second screen grid completely enclosing said first screen grid and having portions thereof spaced from said first screen grid, and a control electrode mounted within the space between said first screen grid and said second screen grid.

4. An electron discharge device including a cathode for emitting electrons, a first cylindrical screen grid having an elliptical right section concentric with said cathode, a second circular cylindrical screen grid concentrically surrounding said first screen grid and forming an enclosed space on either side of said first elliptical screen grid, a plurality of side rods each providing a common support for said screen grids along their cylindrical surfaces, a control grid comprising two cylindrical portions, said portions being mounted concentrically with said cylindrical grids, and one of said portions being within each enclosed space.

5. An electron discharge device comprising an envelope, a first and second screen electrode mounted within said envelope, said first screen electrode being concentric with and enclosing said second screen electrode, said first and second screen electrodes each adjoining the other at respectively two portions thereof, a pair of common side rods, each of said side rods supporting both said first screen electrode and the said second screen electrode at one of the adjoining portions,

said first and second screen electrodes forming two enclosed spaces therebetween, a third control electrode having two portions thereof, one of said two portions mounted within each of said enclosed spaces.

5 6. An electron discharge device including a first screen grid, a second screen grid completely enclosing said first screen grid, means common to said first and second grids supporting said grids, said grids providing an enclosed space therebetween, a third control electrode within said enclosed space, means rigidly supporting said third electrode within said enclosed space.

15 7. An electron discharge device comprising a first cylindrical screen grid, a second cylindrical screen grid completely enclosing and concentric with said first screen grid, side rod means common to said first and second grids supporting said grids, said grids providing two enclosed spaces 20 therebetween, a third grid electrode including two portions, one of said portions being within each of said enclosed spaces, means rigidly supporting said third grid portions respectively within said enclosed spaces.

25 8. An electron discharge device including a first cylindrical screen grid having an elliptical right section, a second circular cylindrical screen grid concentrically surrounding said first screen grid, a pair of spaced side rods positioned along 30 the transverse axis of said first elliptical grid, said first and second screen grids being rigidly mounted on said pair of side rods whereby two enclosed spaces are formed between said first and second grids, a control grid comprising two portions, 35 a second pair of side rods, one of said second side rods supporting one of said portions concentrically with said cylindrical grids within each of said enclosed spaces.

40 9. An electron discharge device including a cathode for supplying electrons, an anode spaced from said cathode for receiving said electrons, a first control electrode surrounding said cathode, a first and second foraminous screen electrode 45 enclosing said first electrode and said cathode, said electrodes mounted between said cathode and said anode, one of said screen electrodes having two spaced portions thereof adjoining to the other screen electrode, a pair of common side rods, each of said side rods supporting both said 50 first and second screen electrodes at one of said adjoining portions whereby two enclosed spaces are formed between said first and second screen electrodes, a second control electrode comprising two portions thereof, one of said portions being rigidly mounted between said first and second screen electrodes and within each of said enclosed spaces.
